UNITED STATES PATENT OFFICE.

WILLIAM S. MCLEWEE, OF NEW YORK, ASSIGNOR TO JACOB J. NICHOLS,
OF BROOKLYN, N. Y.

DESIGN FOR A COMBINED LAMP AND VASE.

SPECIFICATION forming part of Design No. 13,335, dated October 10, 1882.

Application filed May 27, 1882. Term of patent 14 years.

To all whom it may concern:

Be it known that I, WILLIAM S. MCLEWEE, of New York, in the county and State of New York, have originated and produced a new 5 Design for a Combined Lamp and Vase, of which the following is a specification.

My design consists in various features, hereinafter particularly described and claimed.

In the accompanying drawings, Figure 1 is 10 a side view of a combined vase and lamp embodying my design, and Fig. 2 is a central vertical section thereof.

Similar letters of reference designate corresponding parts in both figures.

15 I have not shown a burner in connection with the lamp; but any suitable style of burner may be used. The vase or holder for the lamp consists of a base portion, B, and an upper portion, C. The base portion B may be made 20 of brass or other metal, and is of an ornamental configuration, embellished externally with rich designs cast, engraved, impressed, or embossed upon or in it. The upper part is formed of glass, porcelain, or other ceramic ware decorated or ornamented with any appropriate designs. Preferably the upper portion will be 25 made of transparent or opal glass having painted on it representations of flowers or other devices or articles, as then it may be 30 made cheap and highly ornamental. It is here shown as made in the form of a cylinder

and as having its lower edge fitting into the base portion B, a shoulder, a, made in the form of an ornamental bead or beads, resting on the top of the said base portion, serving to support 35 it on the latter. An ornamental ring, band, or crown of metal, D, surrounds and forms part of the upper portion, C. It fits over the upper edge and rests upon a shoulder, b, formed of a bead or beads extending from the said 40 upper portion.

What I claim as new, and desire to secure by Letters Patent, is—

1. In a combined lamp and vase, the design for a base portion, substantially as set forth. 45
2. In a combined lamp and vase, the design for an upper portion, substantially as set forth.
3. In a combined lamp and vase, the design for an upper portion and ring, band, or crown, substantially as set forth. 50
4. In a combined lamp and vase, the design for a base portion and an upper portion, substantially as set forth.
5. In a combined lamp and vase, the design for a base portion, an upper portion, and a ring, band, or crown, substantially as set forth. 55

W. S. MCLEWEE.
